US00D938847S

(12) **United States Design Patent** (10) Patent No.: **US D938,847 S**
(45) Date of Patent: **** Dec. 21, 2021**

(54) **DIAL AND VISIBLE PARTS OF THE WATCH
MOVEMENT**

(71) Applicant: **LVMH SWISS MANUFACTURES
SA**, La Chaux-de-Fonds (CH)

(72) Inventor: **Christoph Behling**, Londres (GB)

(**) Term: **15 Years**

(21) Appl. No.: **35/510,122**

(22) Filed: **Jul. 9, 2019**

(80) **Hague Agreement Data**

Int. Filing Date: **Jul. 9, 2019**

Int. Reg. No.: **DM/209759**

Int. Reg. Date: **Jul. 9, 2019**

Int. Reg. Pub. Date: **Aug. 21, 2020**

(30) **Foreign Application Priority Data**

Jan. 11, 2019 (WO) IBDM/201368

(51) **LOC (13) Cl.** **10-07**

(52) **U.S. Cl.**

USPC **D10/129**

(58) **Field of Classification Search**

USPC D10/128-130, 124, 126, 38

CPC G04B 11/008; B29C 45/1657
